DRAWER

Lester F. Schroeder, Grand Rapids, Mich., assignor to Metal Office Furniture Company, Grand Rapids, Mich., a corporation of Michigan

Application May 11, 1944, Serial No. 535,145

4 Claims. (Cl. 129—26)

The present invention relates to drawers and more particularly to a drawer for a cabinet or the like.

The primary objects of the instant invention are to provide a drawer of the general character above indicated whereby any of a plurality of sheets encased therein and lying one upon the other may be readily, conveniently and selectively withdrawn therefrom; to provide such a drawer whereby a plurality of sheets therein are protected in flat position while encased; and, to provide such a drawer which is efficient in use and which is reasonably economical in manufacture.

An illustrative embodiment of the invention is shown in the accompanying drawings, wherein—

Figure 1 is a longitudinal sectional view of the drawer showing the same completely filled with a plurality of sheets of blue prints, tracings or the like lying one upon another;

Figure 2 is a similar view but showing the drawer encasing a lesser number of such sheets;

Figure 3 is a view on a smaller scale, showing the manner in which the forward ends of a plurality of sheets encased within the drawer are lifted, making it convenient for the user to selectively withdraw a given sheet or sheets; and

Figure 4 is a fragmentary top plan view of the drawer.

Referring then to the drawings wherein like parts of the structure shown are designated by the same numerals in the several views, the drawer of a cabinet or the like, generally designated 10, is provided with a pull 11 and a stop 12, the outward movement of the drawer being indicated by the arrows as shown in Figures 1-3.

A plurality of sheets of blue prints, tracings or the like 13 encased within the drawer are firmly held in flat position therein by means of the head 14 of an arm 15, said arm being pivotally mounted at one end adjacent the inner surface of the outer end of the drawer 10, all as shown in Figures 1 and 2, wherein Figure 1 shows a full drawer of such sheets whereas Figure 2 shows the drawer encasing a lesser number of sheets.

The bottom 16 of the drawer 10 supports a spaced elevated unsecured floor 17 forwardly thereof and a link 18 pivotally secured to said floor near its under forward end is pivotally secured at its other end to a link 19 whose opposite end is pivotally secured to the underside of the arm 15, the link 19 having a lug 20 adapted to engage the link 18 when it is in its positions shown in either Figure 1 or 3.

Operation

In operation, the drawer is withdrawn from its cabinet or the like by means of the pull 11 in the direction indicated by the arrows in Figures 1-3.

Sheets of blue prints, tracings or the like 13 encased within the drawer 10, whether the drawer is full as shown in Figure 1 or has fewer sheets as shown in Figure 2, are maintained in flat position one above the other by the head 14 of the arm 15.

Upon withdrawal of the drawer, manual lifting of the head 14 of the arm 15 from its position shown in either Figure 1 or 2 to its position shown in Figure 3, tilts the forward end of the floor 17 upwardly, lifting the sheets 13 and making it readily and conveniently possible for the user to selectively withdraw a given sheet or sheets encased within the drawer.

While but one specific embodiment of the invention has been herein shown and described, it will be understood that certain details of the construction shown may be altered or omitted without departing from the spirit of the invention as the same is defined in the following claims.

I claim:

1. In a drawer of the class described, a floor supported by the bottom of the drawer, an arm pivotally secured to the drawer, and a link pivotally secured at one end to the floor whose other end is pivotally secured to one end of a link whose opposite end is pivotally secured to the arm.

2. In a drawer of the class described, a movable floor supported by the bottom of the drawer, an arm pivotally secured at one end to the forward end of the drawer, and a link pivotally secured to the floor whose other end is pivotally secured to one end of a link whose opposite end is pivotally secured to the arm.

3. In a drawer of the class described, a movable floor supported by the bottom of the drawer, an arm pivotally secured at one end to the forward end of the drawer, and a link pivotally secured to the floor adjacent its forward end whose other end is pivotally secured to one end of a link whose opposite end is pivotally secured adjacent the forward end of the arm.

4. In a drawer for a cabinet or the like, a floor supported by the bottom of the drawer upwardly tiltable within the drawer, an arm pivotally secured at one end to the forward end of the drawer, and a link pivotally secured at one end to the floor adjacent its forward end whose other end is pivotally secured to one end of a link whose opposite end is pivotally secured adjacent the forward end of the arm whereby the forward swinging movement of the arm tilts the forward end of the floor upwardly.

LESTER F. SCHROEDER.
